(57) **CLAIM**

The ornamental design for a portable motorcycle lift, as shown and described.

DESCRIPTION

FIG. 1 is a front perspective view of the portable motorcycle lift of the present invention showing my new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a left end elevational view thereof; and,

FIG. 7 is a right end elevational view thereof.
